ANTICHEAT DEVICE FOR GAMES, ETC.

Robert H. Breither, Chicago, Ill., assignor to Raymond T. Moloney, Chicago, Ill.

Application December 2, 1937, Serial No. 177,673

5 Claims. (Cl. 194—97)

The invention relates to an anticheat means for use with amusement apparatus, vending machines, etc., which are released for operation by a coin slide.

These coin slides, as is well known in the art, usually embodying means to engage a fraudulent coin or check, such as one having a hole therein, or being magnetic, to lock the slide against making the full stroke thereof necessary to release the apparatus. The slide serves, when properly operated, to move a link or the like to release the apparatus for operation. Sometimes, unscrupulous persons, using an authentic coin may place one hand around the coin slide and with the other hand move the slide inwardly to a mid point or less than the full stroke and then with their free hand suddenly and sharply jar the slide so that its inner end without any further inward sliding movement will suddenly jar the release linkage, and by the inertia so set up, cause operation of the linkage without passing the slide or coin its full stroke. The hand surrounding the slide acts as a stop to prevent the slide from making its full stroke. In this manner the apparatus may occasionally be operated by the inertia of shock imparted by the coin slide to the interior release linkage mechanism without losing the coin, since the slide cannot make a full stroke and discharge the coin. This form of petty cheating is sufficiently prevalent to create a problem.

Accordingly, the main object of the invention is to provide means for apparatus of the kind mentioned, to operate a signal or analogous tell-tale device by inertia created by sudden shock imparted through the coin slide.

Another object of the invention is to provide an improved cheat proof means operatively associated with a coin slide in the manner and for the purposes stated.

Still another object is to provide a swinging arm, inertia operated through shock transmitted by the coin slide, to close a contact and circuit for an electrical signal of any suitable character.

Other important objects will become apparent to those skilled in this art as the disclosure is more fully made.

Briefly these objects may be achieved in an amusement or vending apparatus releasable for operation by means of a coin slide mounted in the wall of the usual cabinet containing the apparatus. When the coin slide is manually pushed into the cabinet with a coin, the inner end thereof upon completing its full stroke will engage and push a linkage, or equivalent mechanism, to release the apparatus for operation. If the stroke of

the slide is restrained short of its full stroke and then has a sudden jar or shock imparted thereto, the inner end of the slide would engage the release linkage sufficiently to transmit said shock and cause the linkage to be moved and perform its release function and operation of the apparatus. By associating a free swinging member, or weighted pendulum arm with the linkage in a manner to be swingable by such inertia shock, it is possible to use such arm to close an electrical contact and circuit to cause operation of a suitable signal device, such for example, as an electric lamp to give a visual indication that the machine is being fraudulently manipulated.

In the illustrative embodiment of the invention herein shown, a pin ball amusement game apparatus is depicted by way of example. In the drawing:

Figure 1 is a plan view of a part of a pin ball type of game, with the game board partly broken away to expose the mechanism of this invention disposed therebelow; and,

Figure 2 is a side sectional view of the structure, taken along the line 2—2 of Figure 1, looking in the direction of the arrows.

The apparatus shown embodies a cabinet 10, having a front wall 11, carrying a manually slideable coin slide 12, in the front wall thereof, in any conventional manner. When the slide carries a coin, or is coin released, so to speak, it may be pushed into the cabinet, the instroke thereof being utilized to cause engagement of the inner end of the slide with an appropriate interior mechanism to cause release of the apparatus for operation. As shown, the game illustrated has a top board, or ball rolling table 13, ball receiving holes 14, and a ball receiving passage 15 at the low end of the table, the table being sloped slightly from the horizontal in a manner common in this art. The cabinet 10 at its top is closed by the usual glass panel cover 16.

The game apparatus includes a normally open, spring blade contact switch 17 carried appropriately on a wall of the cabinet, said switch being in an electrical signal circuit 18 with a source of electrical energy 19 and a suitable signal, such for example, as the electric lamp 20. It is desirable to turn on this lamp as a signal, or visual indication, every time an unscrupulous player deliberately restrains or jams the coin slide 12 and by suddenly shocking same attempts to utilize the inertia so developed to cause release of the interior parts in a dishonest manner. To bring about this indicator result the interior release parts of the game are constructed to include an

inertia responsive element which under the circumstances described will cause the switch 17 to be closed.

The release parts include an upright lever 21 pivoted at its lower end by a pin 22 to a mounting bracket 23 carried on an adjacent side wall of the cabinet. The upper end of this lever 21 is in a position to be engaged by the inner end of the coin slide 12 upon an instroke of the latter 10 in a manner that will be quite apparent from the dotted line and full line showing in Figure 2.

This lever 21 has pivotally connected to it, a releaser member in the form of a link 24, the free end, or rear end of which is guided between 15 rollers 25 carried on a bracket 26 mounted on the adjacent side wall of the cabinet. The rear end of the link is bent at a right angle as at 27 to carry an adjusting screw 28 for accurately determining the length of the link in accordance with the 20 stroke it is intended to make in relation to the position of the interior parts of the apparatus to be released. It is to be understood that this screw 28 is the end of the link which engages and pushes the parts to be released. Such parts are 25 not shown as it is unnecessary.

Adjacent the link is pivotally carried a swingable arm or pendulum 29 in a bracket 30, said arm being fulcrumed intermediate its ends, with the lower end thereof carrying a weight 31 swingable with the arm in an arc so as to enable it to engage and close the contact switch 17, as shown. The link, or bar 24 carries an abutment or pin 32 extending laterally so as to engage and swing the arm 29, it being the upper end of the arm that 35 is so engaged as will readily be seen. This arm 29 is limited to swinging movement in an arc, the length of which is determined by oppositely disposed stop pins 33 and 34 extending from the cabinet wall. A weak coil spring 35 connects between the wall and the upper end of the arm 29 to hold the lower end of the arm yieldably against the stop pin 33.

In the normal, natural push in stroke of the coin slide the lever 21 and link 24 are easily moved 45 to cause the inner end 28 thereof to engage and release the releasable parts of the apparatus. After these parts are released or set up for operation a spring not shown serves to retract the slide 12, or it may be retracted by hand. Such 50 natural or easy operation of these releaser parts will not affect the arm 29 or will merely swing it so slightly that it cannot engage the switch 17 and close it. However, under sudden shock as when the slide 12 is held part way in and then 55 sharply pounded, an inertia force is set up through the link 24 that will cause the pin 32 so sharply to strike the arm 29 as to make it swing to the dotted line position shown in Figure 2, where the weighted end 31 thereof will engage and 60 close the switch 17, thus operating the signal or indicator 20 to show a fraudulent release of the apparatus. Thus, inertia transmitted through the coin slide 12 is utilized to thwart cheaters.

It is the intention to cover all changes and 65 modifications not departing from the spirit and scope of the invention.

What is claimed is:

1. In an apparatus of the class described, a cabinet carrying a coin slide movable thereinto to release and adapt interior parts for operation, releasing means comprising a lever fulcrumed in the cabinet and swingable by the coin slide on the instroke of the latter, a releaser link operable by the lever, a swingable member operatively associated with the link, and a normally open contact switch for an electrical indicator circuit included in the apparatus, said member adapted to engage and close the switch when the slide is given a quick sudden stroke. 10

2. In an apparatus of the class described, a cabinet carrying a coin slide movable thereinto to release and adapt interior parts for operation, releasing means located in the cabinet and operable by the coin slide on the instroke of the latter to release the interior parts for operation, means, operatively associated with the releasing 15 means and a normally open switch for an electrical indicator circuit included in the apparatus, the last named means being operable to close the switch when the slide is given a quick sudden stroke. 25

3. In an apparatus of the class described, a cabinet carrying a coin slide movable thereinto to release and adapt interior parts for operation, releasing means comprising a shiftable member carried in the cabinet and movable upon the instroke of the coin slide, a normally open switch for an electrical indicator circuit included in the apparatus, and a pendulum member operatively associated with the shiftable member and operable upon a quick sudden stroke of the coin slide 30 to effect closing of the switch. 35

4. In an apparatus of the class described, a cabinet carrying a coin slide movable thereinto to release and adapt interior parts for operation, releasing means comprising a shiftable member carried in the cabinet and movable upon the instroke of the coin slide, a normally open switch for an electrical indicator circuit included in the apparatus, a pendulum member operatively associated with the shiftable member and operable 40 upon a sudden quick stroke of the coin slide to effect closing of the switch, a stop for limiting movement of the pendulum in one direction, and resilient means for yieldably holding the pendulum normally seated against said stop. 50

5. In an apparatus of the class described, a cabinet carrying a coin slide movable thereinto to release and adapt interior parts for operation, a lever fulcrumed in the cabinet and movable by the slide on the instroke of the latter, a link pivotally connected to the lever and movable thereby to release the interior parts, an abutment on the link, a normally open switch for an electrical signal circuit included in the apparatus, and a pendulum member operatively associated with 55 the link and engageable by the abutment to be swung thereby upon a sudden quick stroke of the coin slide to effect closing of the switch. 60
